Primary Examiner — Paula Greene(74) *Attorney, Agent, or Firm* — Plumsea Law Group, LLC(57) **CLAIM**

The ornamental design for an ear bud adapter, as shown and described.

DESCRIPTION

FIG. 1 is a perspective view of a right-handed embodiment of an ear bud adapter showing our new design;

FIG. 2 is a side elevational view of one side thereof;

FIG. 3 is a side elevational view of the opposite side thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view of a left-handed embodiment of the ear bud adapter showing our new design;

FIG. 9 is a side elevational view of one side thereof;

FIG. 10 is a side elevational view of the opposite side thereof;

FIG. 11 is a front elevational view thereof;

FIG. 12 is a rear elevational view thereof;

FIG. 13 is a top plan view thereof; and,

FIG. 14 is a bottom plan view thereof.

The broken line showings form no part of the claimed design.

1 Claim, 8 Drawing Sheets---
